BERET

Isidore Zelniker, New York, N. Y.

Application March 28, 1949, Serial No. 1,677

Term of patent 3½ years

(Cl. D3—13)

To all whom it may concern:

Be it known that I, Isidore Zelniker, a citizen of the United States of America, and a resident of the city of New York, Bronx County, State of New York, have invented a new, original, and ornamental Design for a Beret, of which the following is a specification, reference being had to the accompanying drawing, forming a part thereof.

In the drawing,

Fig. 2 is a top plan view thereof.

Fig. 3 is an enlarged sectional view thereof taken in the plane of line 3—3 of Fig. 2.

I claim:

The ornamental design for a beret, substantially as shown.

ISIDORE ZELNIKER.
